United States Patent Office

Des. 193,472
Patented Aug. 28, 1962

193,472

GO-CART

Clifford Brooks Stevens and David Brooks Stevens, Fox Point, Wis., assignors to Gilson Bros. Co., Plymouth, Wis., a corporation of Wisconsin

Filed Apr. 13, 1961, Ser. No. 64,715

Term of patent 14 years

(Cl. D14—3)

Fig. 4

Fig. 5

Fig. 6

FIG. 1 is a perspective view of a go-cart embodying our new design.

FIG. 2 is a side elevation thereof.

FIG. 3 is a plan view thereof.

FIG. 4 is a front elevation thereof, with portions omitted for clarity of illustration.

FIG. 5 is a rear elevation thereof.

FIG. 6 is a perspective view of the body portion of the

go-cart shown in FIG. 1 with portions omitted for clarity of illustration.

We claim:

The ornamental design for a go-cart, as shown.
